PACKING

Evarts G. Loomis, Newark, N. J., assignor to The
Dorin Corporation, Union City, N. J., a cor-
poration of New Jersey

Application February 5, 1930, Serial No. 426,072

4 Claims. (Cl. 154—45.5)

This invention relates to packings. More par-
ticularly, it relates to packing materials having
definite lengths and high internal strength,
whereby they may be distorted and successfully
5 withstand the stresses occasioned thereby with-
out any substantial disintegration.

Prior to this invention, packing compositions
have been molded and formed into definite lengths
of suitable cross-sections. These materials were
10 incapable of resisting the stresses produced in the
distortion thereof. Thus, when they were care-
lessly and roughly handled, pulled, bent, flexed,
coiled or subjected to any similar operation, the
cohesion between the various components was de-
15 stroyed. To minimize this defect the packings
were provided with exterior coverings. Though
these coverings prevented the loss and scattering
of the ingredients of the product when distorted,
nevertheless they did not impart any internal
20 strength to the molded product.

I have found that by interiorly reinforcing the
molded composition, I can produce a packing
having a high internal strength capable of suc-
cessfully resisting the stresses occasioned by dis-
25 torsion resulting from pulling, bending, flexing,
coiling or the like.

It is therefore an object of this invention to pro-
duce a packing of high internal strength comprising
an interiorly reinforced molded packing com-
30 position.

Another object of this invention is to provide
a packing of high internal strength comprising a
molded packing composition reinforced with
35 strands or thread-like materials incorporated
therin and extending preferably longitudinally
therethrough.

Additional objects will appear from the follow-
ing description, appended claims and accompan-
ying drawing forming a part of this invention and
40 in which:

Figure 1 is a perspective view of a packing pre-
pared in accordance with the principles of this
invention.

Figure 2 is a cross-section of the packing illus-
trated in Figure 1.

Figure 3 illustrates one form of a die mecha-
nism capable of being employed in the manufac-
ture of the packing material.

Figure 4 is a detail illustration of the means for
50 embedding the strand in the packing composition.

According to this invention, a plastic packing
composition is pressure molded by being extruded
through any suitable shaping mechanism, such as
a die, whereby it is given a definite shape and
55 length. At some stage in the shaping or the ex-

trusion a strand of material is embedded in the
composition in such a manner that it is incorpo-
rated and extends longitudinally through the
product. The incorporated strand reinforces the
product and imparts thereto a relatively high
5 internal strength which permits distortion and
pulling without any substantial disintegration.
To more clearly explain the invention, reference
is made to the accompanying drawing in which
like reference numerals designate like parts or
elements.

Referring now to Figure 1, the reference num-
eral 1 designates the molded or extruded pack-
ing composition of any type and the reference
numeral 2 designates the strand incorporated
therin. For reasons which will become apparent
15 from the hereinafter described method, the pack-
ing may be provided with a covering 3, preferably
spirally wrapped thereon, of a frangible material.

The packing constituting this invention may be
made in various manners. In Figure 3 there is
illustrated one form of a device which may be em-
ployed to produce the packing. This device con-
sists of a die member 4 having a passage 5 ex-
tending therethrough and terminating at one end
20 thereof in an opening 6 through which the pack-
ing composition is discharged from the device.
The shape and size of this opening depends on
the desired cross-section of the packing. If the
packing is to be circular in cross-section, then this
25 hole is made round; on the other hand, if the
packing is to be made elliptical, square or of any
other configuration, then this aperture is made
of the corresponding contour. The other end of
the passage is suitably connected to any well
30 known means for supplying and feeding the pack-
ing composition to be processed in the die.
The passageway 5 is made of different dia-
35 metrical dimensions throughout its length, as
indicated by the reference numerals 7, 8 and 9.
Between the various sized cross-sections there are
provided shoulders 10 and 11 which aid in reduc-
ing the material to the desired size as well as
finishing the surface of the packing.

Suitably disposed in the die member and pref-
erably adjacent the shoulder 11 are means which
groove or channel the composition and embed the
strands 2 in the groove. These means comprise
a bolt-like member 12 having a shank, the termi-
nal portion 13 of which is smaller in cross-section
than the threaded portion 14. By means of the
threads 14 cooperating with a threaded hole in
the die, the member 12 may be adjustably mount-
ed in any predetermined position. The member
12 is also provided with a passage 15 extending
50

through the center thereof for guiding the strand 2, as will presently appear. When in proper operative position the terminal portion 13 extends into the passage 5, as clearly illustrated in Figure 5 3, and serves to form a channel or groove in the material engaging therewith. The strand 2, suitably disposed on a freely rotating spool, is fed through the passage 15, and, as the composition is grooved, it is disposed therein. The material 10 at this stage of the process is continued to be forced through the die passage. As it passes the shoulder 11 prior to entering that portion of the passage designated by the reference numeral 9, said shoulder smooths over and fills up the grooves, 15 whereby the strand 2 is embedded in the mass and hidden from view upon exit from the aperture 6.

The number of mechanisms for grooving the composition and embedding the strand depends 20 on the number of reinforcing elements desired in the final product. If, for instance, a single reinforcing element is desired, then only one such member is necessary. On the other hand, if a plurality of reinforcing elements is desired, then 25 a corresponding number of these mechanisms is employed.

Due to the threaded construction and arrangement, the member 12 may be adjusted to any desired position. Thus, the reinforcing elements 30 may be located at any predetermined positions in the product.

The reinforcing elements may be formed of any 35 of a number of materials. For instance, they may be strands, such as threads or cords of any textile material including cotton, hemp and artificial silk, or they may be formed of rubber, wire and the like. It is only essential that the reinforcing elements be of such a composition that does not interfere with the successful operation 40 of the packing material in its intended use.

The packing material, as it comes from the die, possesses a high internal strength. It is capable of withstanding the stresses occasioned by distortion and longitudinal pull.

45 The product, if desired, may be encased or coated with any frangible and easily disruptible materials. It is obvious that numerous materials are suitable for this purpose. I prefer to spirally wrap a ribbon of material, such as regenerated cellulose, in such a manner that the adjacent convolutions thereof overlap.

This invention may be successfully practiced with lubricating compositions comprising finely

divided anti-friction metallic materials, asbestos and/or other fibers, graphite admixed with a suitable binder, such as an oil or wax, or a composition binder, including a colloidal hydrocarbon, such as rubber homogeneously mixed with menhaden oil.

5 The packing constituting this invention may be used to pack glands, stuffing boxes and the like. It is particularly adapted for packing of a gland having a moving part, such as a piston, reciprocating therein due to its lubricating quality. To pack such a structure it is only necessary to remove the follower, wind the packing about the shaft in any manner, and then force the packing into the gland by screwing down the follower. In 10 case a covered packing is employed, the covering will be disrupted in a substantially short time by the reciprocation of the moving parts, thus quickly and readily permitting the useful ingredients to function.

15 Since it is obvious that various changes and modifications may be made in the specific details above described, this invention is not restricted thereto except as defined by the appended claims.

20 I claim:

1. A packing of high internal strength comprising a die-extruded packing composition containing finely divided anti-friction metallic materials, fibrous materials, a solid lubricant and a binder, and having one or more strands incorporated in 30 the molded composition and extending longitudinally therethrough.

2. A packing of high internal strength comprising a die-extruded packing composition containing finely divided anti-friction metallic materials, 35 fibrous materials, a solid lubricant and a binder, and having one or more metallic strands incorporated in the molded composition and extending longitudinally therethrough.

3. A packing of high internal strength comprising a die-extruded packing composition containing finely divided anti-friction metallic materials, fibrous materials, a solid lubricant and a binder, and having one or more rubber strands incorporated in the molded composition and extending longitudinally therethrough.

4. A packing of high internal strength comprising a die-extruded packing composition containing finely divided anti-friction metallic materials, fibrous materials, a solid lubricant and a 45 binder, and having one or more textile threads incorporated in the molded composition and extending longitudinally therethrough.

EVARTS G. LOOMIS.
